BREW COOLING

Frederick G. Merckel, Montclair, N. J., assignor
to Novadel-Agene Corporation, Newark, N. J.,
a corporation of Delaware

Application July 26, 1940, Serial No. 347,654

7 Claims. (Cl. 257—15)

The present invention is concerned with the art of temperature conditioning, more particularly of liquids stored in dispensing containers and is more especially useful in cooling at the place of sale, of brew contained in transportation packages or kegs.

The invention has its major application to the so-called "Kooler Keg" system of the general type disclosed and claimed in Patent No. 2,051,013, issued August 11, 1936, to Herman E. Schulse, as well as to various specific applications of the said "Kooler Keg" system, as for instance, that generally claimed in Reissue Patent No. 21,352, granted February 13, 1940, on application of John Panagopoulos, in all of which "Kooler Keg" systems the keg contents are internally cooled by the circulation of cold water therethrough.

Among the objects of the invention are to provide an installation of the above type, involving an otherwise conventional keg construction of metal, single walled or double walled or of wood, with appurtenances easily incorporated or installed therein for cooling the keg contents, and easily connected in the cooling circuit, which appurtenances are of enhanced simplicity in construction, of reduced cost, bulk and weight, devoid of yielding or flexible elements, of such ruggedness as to withstand the severest mechanical shock to which beer kegs are subjected in the course of transportation, which are compatible with the use of conventional equipment for cleaning, racking and tapping the keg, and are easily inspected and repaired, without the necessity of taking part or opening the keg for that purpose.

In its essence, the invention involves the incorporation of one or more open pockets, desirably metal shells, fixed within the structure of the keg, submerged in the keg contents and in heat conductive relation therewith, some or all of which pockets preferably depend from the upper head of the keg. Each of the pockets closes the corresponding opening in the keg wall structure at which it is retained in the keg. The keg is set up in the cooling circuit by closing the pocket mouths, preferably with a removable plug and the water or other cooling fluid is circulated through the pocket by way of inlet and outlet ducts therat. A flow guide insert associated with the plug compels the cooling fluid to pass through substantially the entire depth or length of the pocket on its way from the inlet to the outlet. Desirably the flow guide insert is carried by the closure and the inlet and outlet ducts extend through said closure at opposite sides of said

insert. To assure the desired area of pocket surface contact with the brew for efficacious cooling with chilled water or other cooling fluid, it is desirable to use a plurality of pockets of smaller diameter in each keg rather than one tube of larger diameter, as better distribution of refrigeration and considerably less reduction in the effective volumetric content of the keg as well as in the strength of the upper head is thereby attained.

In the accompanying drawings in which are shown one or more of various possible embodiments of the several features of the invention,

Fig. 1 is a diagrammatic view of a fragment of a cooling installation showing various alternative embodiments of inserts and a pair of kegs, each with one insert installed and another one in the course of installation.

Fig. 2 is a cross-sectional view on a larger scale showing a part of the keg at the left of Fig. 1,

Fig. 3 is a perspective view of the insert structure shown in Fig. 2,

Fig. 4 is a plan view of a modified form of keg,

Fig. 5 is a sectional view taken on line 5—5 of Fig. 4,

Fig. 6 is a cross-sectional view on a larger scale showing a part of the keg shown at the middle of Fig. 1, but somewhat modified,

Fig. 7 is a cross-sectional view taken on line 7—7 of Fig. 6,

Fig. 8 is a view similar to Fig. 6 showing a modification of the insert of Fig. 6 and showing the installation in a wooden rather than a metal keg, and

Fig. 9 is a view similar to Figs. 2, 6 and 8 of a further modification.

In the diagrammatic view of Fig. 1, are shown the water mains 10 and 11 encased in heat insulating conduit 12 as ordinarily used in the "Kooler Keg" system. Cooling liquid, preferably cold water, would be circulated through said pipes by a pump 13 submerged in a liquid cooling box 14, the contents of which are kept slightly above the freezing point by a coil 16 through which the primary refrigerant is circulated by any suitable compression unit 18. Flexible branch hose extend in pairs h' and h'' from the respective mains. The free ends of said pairs of hose extend into or connect to corresponding apertures in a closure, desirably a plug p , through one of which the cooling fluid is propelled into a cavity in the keg hereinafter to be described and through the other of which the cooling liquid leaves the keg.

Only two kegs K' and K'' are illustratively

shown actually installed in Fig. 1, although in practice a greater number might be connected as in the said Schulse patent. The keg has mounted in the wall thereof, preferably two or more separate and distinct pockets or shells S of metal or other good heat conductive material, which extend across nearly the entire keg interior, and are submerged in the brew contained therein. Each pocket is hermetically sealed about the opening through which it is introduced as for instance in the upper head, thereby to prevent access of air to the brew contained in the keg, or leak of brew therethrough. Preferably the pockets are of circular cylindrical form, but other columnar shell structures would be useful in carrying out the invention. Desirably the keg wall and the pockets are of the same metal or alloy, thereby to avoid electrolytic action or corrosion. In the embodiment shown in detail in Fig. 2 and generally shown at the left in Fig. 1, the keg is a single walled metal structure, and pocket S is provided with a narrow outturned flange 28 at its upper end superposed over and welded to the rim of an aperture 18 with head, through which the pocket extends into the interior of the keg.

The plug p is desirably of rubber and has inserted therein the short tubes 21 and 22 over the protruding upper ends of which the branch hose ends h' and h² are telescoped. The plug also has affixed thereto a flow guide piece for the cooling fluid, designed to direct the same downward from the inlet hose branch h' substantially the depth of the pocket, before it can return on its way to the outlet branch hose h².

In the particular embodiment illustratively shown in the keg of Figs. 1 and 2 and separately shown in the perspective view of Fig. 3, the flow guide piece is a baffle plate F of suitable metal or of plastic bonded or connected to the plug p with its width extending diametrically therewith across between the inlet and the outlet ducts 21 and 22. The baffle plate is preferably of width substantially equal to the bore diameter of the pocket S and is of length such as to extend nearly but not quite to the bottom wall 26 of said pocket. In Fig. 1 the keg is illustratively shown with two pockets S affixed in the upper head thereof and corresponding baffle plates F are removably affixed therein. The plug p' at the left in keg K' is shown in place, while the plug p² at the right is shown in the process of being applied. It will be seen that if the outer diameter of the pockets is 2½ inches and their length 17 inches, the combined surface area of cooling metal of both of said pockets exposed to the contents of the filled 15½ gallon keg is about 277 square inches.

The two pockets leave unobstructed the keg diameter through the racking hole 27 and the depth from the tapping aperture 28. Accordingly, the cooling pockets in nowise interfere with the cleaning, racking and tapping of the keg by use of conventional equipment for the purpose. Where the single wall non-heat-insulated metal keg K' illustratively shown is used, it will be understood that it desirably is cooled within a suitable heat insulating hood or cabinet (not shown) or alternatively the keg is kept in a cool room.

As shown in Figs. 4 and 5, one of the cooling pockets S is near the tapping aperture 28 for more direct application of the cooling at the region of the keg from which the brew is drawn. To apply additional refrigeration near the bottom of the keg, a transverse cooling pocket S', similar to that already described may extend

across the lower part of the keg, near the draft tube.

In the diagrammatic view of Fig. 1 is illustrated in addition to the branch connections shown applied to keg K' a further alternative set of conduit connections as incorporated in the fixed installation in the tap room and applied to keg K² which is shown equipped with cooling pockets S identical with those of keg K'. Each branch conduit pair H', H² is affixed to a corresponding plug P as previously described. Here the single pair of branch conduits H' and H² may serve two or more cooling pockets, by attaching the inlet conduit H' to the first one, the outlet conduit H² to the last one and using jumper connectors / to connect the cooling attachment for series flow.

Illustratively a different form of flow guide insert F' as more fully shown in Fig. 6 to be hereafter described is attached to plug P, to be inserted in the pockets of the keg to be cooled therefrom. There is also illustratively shown in Fig. 1 two pairs of branch connections each designated h' and h² each pair connected through a corresponding plug P. The flow guide insert F' depending from each of said latter plugs, is shown as a further embodiment hanging from the mains and ready to be introduced into a keg pocket. This embodiment is more fully detailed in Fig. 9 to be hereafter described.

The operation may be briefly set forth. The brew being delivered to the tap room in a keg permanently equipped with the empty pockets S submerged in the brew, is simply moved to the proper place at the cooling main and the respective flow guide inserts F, F' or F² as the case may be, depending from the cooling main structure 12 are simply inserted into the corresponding pockets S and the plugs p, P thereof are pushed home into the mouths of said pockets. When the cocks c in the respective branches are thereupon opened, cooling fluid from the main 10 is passed into the respective pockets. In this action the cooling fluid passes downward through inlet 21 about the lower end of the flow guide insert of the pocket (in keg K' about baffle F), and thence upward through the outlet duct 22 in continuous circulation. Short circuiting of the cooling fluid through the pocket is thus precluded. It will be noted that the cooling effectiveness is a maximum near the bottom of the keg as is desired, since at that region there is provided in addition to the cylindrical surface of the pocket the added cooling area of the circular bottom 26. By reason of the relatively large surface area of the two metal pockets submerged in the brew, the cooling is quite as effective as in the Schulse Patent No. 2,051,013 but as previously set forth the embodiment of Figs. 4 and 5 affords further refrigeration especially near the bottom of the keg.

After the keg has been drained, it is disconnected from the system by simply drawing out the plugs p or P and withdrawing the inserts, permitting them to hang in place as shown at the right in Fig. 1. The keg when rolled into the yard will automatically be drained of any cooling water or liquid remaining in the relatively large bore pockets S and such draining is promoted by the outwardly flaring mouth wall 33 of the pocket bore.

The cooling pocket of the keg being of structure substantially as rigid as that of the wall of the keg itself, and being rigidly and permanently affixed in the keg, the same will withstand the severe punishment to which it is ordinarily subjected in transportation to and from the brewery.

The keg admits of being readily cleaned and pitched in the brewery by the conventional equipment used there and can be readily racked and tapped since the pockets built into the keg are clear of the diameter through the conventional racking hole.

The submerged outer walls of the pockets, that come into contact with the brew are hermetically sealed at all times within the brew and so cannot foul the brew and they are moreover cleaned as an incident to cleaning the keg itself before racking. The inner wall of the pockets which is exposed to the atmosphere during transit of the filled kegs does not enter into contact with the brew and so presents no hygienic problem. The flow guide insert need not be washed or cleaned, as the water or other cooling fluid circulating therethrough in the pocket can never come into contact with the brew.

The present arrangement effects economy in initial cost as compared with constructions in which the entire cooling conduit including an inlet and an outlet end or duct are built into the keg, for the flow guide insert is a permanent part of the tap room installation, to be introduced into the pocket of the keg as the same is placed on the cooling line, as distinguished from constructions in which such element is built into each of the many thousands of kegs used by the brewery.

In Fig. 6 is shown an alternative embodiment of pocket structure S' and of insert in a keg structure illustratively similar to that shown at S in Fig. 2. The pocket is here illustratively shown with a number of longitudinal fins 30 extending the height thereof and effecting a great increase in the cooling surface area exposed to the brew and thereby enhancing the cooling efficacy of the device. By this arrangement, a single pocket may be rendered almost as efficacious for cooling as two plain pockets of corresponding caliber. For the insertion of the tube with its protruding fins, the aperture 31 through which the same is inserted in the keg, must be correspondingly larger than the aperture 18 used in the embodiment of Fig. 2. Therefore, the rolled over bead 20 of the pocket structure is welded to a disk 32 which closes or seals the opening 31 and is welded thereto.

Illustratively the flow guide piece is tubular, in form as shown at F' . Preferably the removable plug p of the insert accommodates the reduced upper end 35 of the tubular flow guide which diverges as at 36 to a cylindrical tube 37 extending, as shown, to near the bottom of the pocket. Desirably the tube 37 is of cross-sectional area about half that of the interior of pocket S' , so that the rate of flow of cooling fluid through the tube 37 is about the same as that of the return about the tube through the pocket S' .

In Fig. 8 is shown illustratively the mode of application of the pocket S^2 to a wooden keg K^2 . To that end the head of the keg is provided with a threaded bushing 38 rolled thereover as at 39 and the mouth $38'$ of the pocket S^2 has a slightly thickened wall which is threaded as shown for secure liquid-tight fit.

In Fig. 8 there is also illustratively shown a check valve 40 near the bottom of the flow guide tube F' , which latter is of the same general construction as that of Fig. 6. Valve 40 is linked at 41 to the side of the tube 37 . The valve readily opens in operation of the system, the cooling fluid entering through the port 42 in the plug P and leaving by way of insert tube 31 through pipe 43 . When, after the keg has been drained for in-

stance, the insert plug p is to be removed, the check valve 40 will cause the contents of tube 37 to be trapped and withdrawn with the plug, so that less water or cooling fluid will remain to be discarded from the pocket S^2 .

In the embodiment of Fig. 9 is shown the application of the pocket illustratively shown at S^3 to a keg K^4 of the double walled metal type. The general construction of this keg is well known and embraces briefly an inner keg wall 45 spaced by spacer rings 46 from an outer keg wall 47 . The heads are parts of the respective inner and outer keg walls and, therefore, also double walled. A bushing 48 is preferably incorporated between the two walls of the upper head 50 and welded in place therein as shown, and it presents a threaded opening 51 into which is removably affixed the threaded enlarged rim 52 of the pocket S^3 .

The insert F^2 shown in Fig. 9 comprises a tube 55 of diameter not much smaller than that of the pocket S^3 . This tube 55 is provided with a rib structure 56 thereabout, which snugly fits the inner wall of the pocket S^3 and affords a long circuitous path for the flow of cooling fluid between the pocket and the insert. Desirably and preferably the rib 56 is helical in form as shown. The bore 55 is fixed in the removable plug P , which has an inlet tube 57 therethrough communicating at 58 with the outside of the tube 55 between consecutive convolutions of the rib 56 near the upper end of said tube. The outlet tube 59 communicates directly with bore 55 of the insert. It will immediately be clear that in operation the cooling fluid is circulated through pipe 57 to enter into the helical space between the pocket and the tube to circulate thereabout and cool the keg contents and then to return from the inner end of the pocket upward through the tube 55 and out by way of outlet pipe 59 .

In this embodiment also is shown a check valve 60 at the lower end of the tube 55 . This check valve is illustratively shown of the poppet type, affording a stem 61 encircled by coil spring 62 and lodged in a cage 63 . It will be seen that in the withdrawal of the removable insert from the empty keg, the check valve 60 will trap the major portion of the water or other fluid cooling contents of the pocket S^3 . Accordingly, when the empty keg is removed, there is less annoyance from the possible wetting of the floor with the water or other fluid remaining in the pockets.

The various pockets are sufficiently large and accessible to admit of ease of inspection for leakage or other possible damage, and removal of foreign matter such as tax stamps or labels which occasionally enter exposed cavities as pointed out in the Schulse patent above identified. Removal of the pocket for replacement is relatively easy in all of the embodiments. In the embodiments of Figs. 8 and 9, an expansion tool applied in the mouth of the respective pockets will serve to unscrew the same without any need for disassembly of the keg.

In the embodiments of Figs. 2 to 6 the defective pocket need merely be severed at its mouth by a welding torch, the remaining rim being then ground off, whereupon a new pocket may be readily introduced and welded in place.

In each of the embodiments of insert, it is noted that the insert tube or baffle constitutes a wall structure which subdivides the cross-section of the pocket into two compartments substantially closed from each other, except near the bottom of the pocket where the compartments are connected in series.

While in general it is desirable to equip each keg with two of the pockets set forth, three or more pockets could be used to advantage. Where three pockets are used, approximately the same total surface area of pocket contacting the brew (i. e., 245 square inches) would be attained if the outer diameter of each pocket were but one and a half (1½) inch instead of 2½ inches. In that event, the approximate displacement of three 1½ inch pockets would be about three pints while that of two 2½ inch pockets is about three quarts. Moreover, the total area of the three holes in the keg head to accommodate the pockets would be 5.1 square inches instead of 9.8 square inches and the weakening of the keg head due to the apertures therein would be correspondingly less.

Substantial flexibility is afforded by the present invention, since less than the full number of the cooling inserts may be used or operatively connected if desired. Thus, where the keg is to be kept on reserve, untapped, and at a temperature sufficiently low to avoid spoilage but not so low as to be suitable for dispensing, it might be desirable to connect only one of the pockets into the cooling circuit.

It will of course be evident that the invention lends itself to installation for as many kegs as are desired, that kegs of various types may be used on one and the same line, that flow guide inserts F, F', F² of one and the same type or of various types may be used conveniently on one and the same system.

While the invention has been shown in an embodiment in which the brew faucets are adjacent the kegs, it is understood that it is also applicable to installations in which the faucet is remote from the keg and the length of brew line to the faucet is enclosed in a conduit with cooling fluid circulating therethrough, and of general type disclosed and claimed in Reissue Patent No. 21,352, granted February 13, 1940, on application of John Panagopoulos.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent is:

1. The combination of a brew cooling transportation package, having a plurality of fluid tight pockets extending through and sealing corresponding apertures in the wall of said package, with closure means removably mounted in the mouths of said pockets, each of said closure means having an inlet and outlet therethrough for cooling fluid and fluid guide means associated with each of said closure means.

2. In a system for cooling the contents of a transportation brew package, a plurality of fluid

5 tight pockets extending through and sealing corresponding apertures in the wall of said package and across substantially the entire interior thereof and in direct contact with the brew contents, closure means removably mounted in the mouths of said pockets, each of said pockets having an inlet thereto and an outlet therefrom for cooling fluid, and fluid guide members associated with the respective closures and extending into the 10 respective pockets, substantially to direct the cooling fluid to traverse the length of each pocket along and in contact with the inner wall thereof on its way from the inlet to the outlet thereof.

15 3. In a brew cooling installation, the combination of a keg having a columnar heat conducting cooling pocket affixed at its mouth at a corresponding opening in the upper head and having a closed bottom near the lower head thereof, said 20 pocket affording a liquid-tight closure at said opening for the contents of the keg, a removable closure for said pocket having an inlet and an outlet therethrough for cooling fluid, said closure having a wall structure affixed thereto, extending nearly the height of said pocket and sub-dividing 25 the cross-section thereof into two compartments substantially closed from each other throughout the length of said insert and in communication with each other substantially only about the inner extremity of said wall structure.

30 4. In a brew cooling installation, the combination of a keg having one or more cooling pockets affixed at the respective mouths thereof to and sealing a corresponding aperture in the upper head, and extending downward therefrom into 35 the contents of the keg to near the bottom thereof, each of said pockets having a removable plug therein with an inlet and an outlet for cooling fluid to be circulated through the corresponding 40 pocket, each of said plugs having a member carried thereby and extending nearly the height of the pocket and serving to direct substantially all of the cooling fluid through the inlet to the opposite end of the pocket on its way to the outlet.

45 5. The combination recited in claim 1 in which the fluid guide means comprises a baffle plate carried by the closure means, disposed between the inlet and the outlet and extending substantially entirely along the pocket to near the closed end thereof.

55 6. The combination recited in claim 1 in which the flow guide means is a tubular conduit having a volumetric capacity in the order of a substantial fraction of the capacity of the pocket, and a check valve at the lower end of said tubular conduit serves to trap cooling fluid therein for withdrawal thereof with said insert.

7. The combination recited in claim 1 in which the fluid guide means comprises a tube carried by 60 said closure means at the outlet therethrough and flares to a bore along the main length thereof of substantially one-half the cross-section of the pocket, and near its lower end has a check valve.

FREDERICK G. MERCKEL.
